DESIGN FOR A TOY AUTOMOBILE OR LIKE ARTICLE

Alfred C. Korte, St. Louis, Mo., assignor to Metal-
craft Corporation, St. Louis, Mo., a corporation
of Missouri

Application December 23, 1933, Serial No. 50,201

Term of patent 7 years

To all whom it may concern:

Be it known that I, ALFRED C. KORTE, a citizen
of the United States, residing at St. Louis, in
the State of Missouri, have invented a new, origi-
nal, and ornamental Design for Toy Automobiles
or Like Articles, of which the following is a speci-
fication, reference being had to the accompan-
ying drawings, forming part thereof.

Referring to the drawings:

Figure 1 is a plan view of the automobile ac-
cording to my design.

Figure 2 is a side elevation of the automobile.

Figure 3 is a front elevation of the automobile.

Figure 4 is a perspective view of the automobile.
The invention relates to the hood and forward
portion of an automobile, those parts to the rear
of the driver's seat being immaterial to the de-
sign. In the drawings, the subject matter which
is shown in solid lines represents that which I
consider as my invention and the subject matter
shown in dotted lines is not material to the inven-
tion.

I claim:

The ornamental design for a toy automobile or
like article, as shown and described.

ALFRED C. KORTE.
